BASEBALL GLOVE

Benjamin B. Stobbe, Ada, Ohio, assignor to Ohio-Kentucky Manufacturing Company, Ada, Ohio, a corporation of Ohio

Application April 17, 1945, Serial No. 588,860

3 Claims. (Cl. 2-19)

1

This invention relates to baseball gloves and is particularly directed to a novel glove construction for use by baseball players occupying the positions of fielders, pitchers, or basemen other than the first base position.

An object of the invention is to provide a novel glove construction which has a reenforced area adjacent the ball pocket portion, said construction precluding the separation of the glove fingers and materially reducing the bending back of said fingers at the moment of ball impact therewith to thereby insure greater facility in catching a ball.

Another object of the invention is to provide a novel glove construction which has a more solid, a deeper and a larger ball pocket than conventional baseball gloves now adapted and used for the aforementioned purposes.

A further object of the invention is to provide a base ball glove structure which permits its wearer's catching hand to assume a more natural position and offers greater protection to the fingers from injury by a ball when it is not caught perfectly. The glove is particularly adapted, by its novel structure, for use in the game of baseball at the pitching position, where batted balls are caught when driven at short distances and at relatively high speeds.

A still further object of the invention is to provide a baseball glove of a simplified construction which is more serviceable because it is composed of a fewer number of parts, fewer seams are required in making it, and consequently there is less likelihood of seams tearing or ripping during use.

Another object of the invention is to provide a baseball glove of the foregoing identified type wherein the palm section has certain fingers interconnected throughout substantially their entire lengths by an integrally formed web portion, the corresponding fingers back sections for the finger portion of the palm section terminating centrally of said fingers backs and also provided with integrally formed web portions which extend between said fingers.

Another object of the invention is to provide a baseball glove of the type described which has a relatively rigid and deep ball pocket principally effected by the interconnection of the index and middle fingers throughout substantially their entire lengths by cooperating web portions formed in the material of the palm and back sections of the glove, said webs terminating short of the said finger tips to form a marginal indentation between the fingers to provide rela-

2

tively flexible finger tips for catching balls hit along the ground, or the like.

Referring now to the drawings, forming a part of this specification and wherein like reference numerals designate corresponding parts throughout the several views:

Fig. 1 is a rear perspective view of my baseball glove.

Fig. 2 is a front perspective view of the glove shown in Fig. 1.

Fig. 3 is an enlarged, cross-sectional view taken on line 3—3 of Fig. 1.

Fig. 4 is a plan view of a blank forming the palm section for my glove.

Fig. 5 is a plan view of a blank forming the back fingers section extending between the index and the middle finger of the glove.

Fig. 6 is a plan view of the blank which forms the back fingers section between the ring and the little finger of the glove.

The embodiment of my invention comprises a baseball glove 10 consisting of an integral palm section 11 and a composite back 12. The palm section is formed with an index finger portion 14 and a middle finger portion 15 which are joined together throughout substantially their entire lengths by an integral web 16. This web portion extends from the bases of said finger portions to a point which terminates just short of said finger tips to thereby form a marginal indentation 17 between said fingers. The finger portions 18 and 19 of the glove for the ring finger and the little finger respectively of the wearer's hand may also be connected throughout substantially their entire lengths by a web 20 which also forms with the tips of the said fingers a marginal indentation 21.

As illustrated in the drawings a relatively deep slit 22 is formed between the middle and the ring fingers portions of the palm section but it is understood that a web could also be interpositioned between these finger sections without departing from the scope and teachings of this invention. The palm section is also provided with integral side extensions 23 and 24 which form the outer half of the backs for the index finger and the little finger respectively.

The composite back 12 for the glove is most clearly illustrated in Figs. 1, 5 and 6 and includes two back fingers sections 25 and 26 which form webs disposed between the index and middle fingers and the ring and little fingers respectively. The outer edge 27 of the back fingers section 25 is joined to the longitudinal edge 28 of the side extension 23 by a sewed seam 29. The rear edge

30 of said section terminates at the hand hole 31. The outer edge 32 of the back fingers section 26 is secured to the inner edge of the side extension 24 by a sewed seam 33, said section being provided with a narrow extension 34 to form the side edge for the hand hole 31.

The back fingers sections 25 and 26 extend between their respective fingers and terminate at the longitudinal center lines thereof, the inner edge 35 of the section 25 being joined to longitudinal edge 36 of an intermediate back finger section 37 by a seam 38, whilst the inner edge 39 of the section 26 is secured to a longitudinal edge 40 of a corresponding intermediate back finger section 41 by a sewed seam 42. These central back finger sections 37 and 41 are shaped to conform to the opening 22 formed in the palm section and may either be integrally connected or joined along their lower longitudinal edges by a sewed seam 43. The tips of the finger portions for the palm section and the tips of the joined back finger sections are secured together by a continuous sewed seam 44.

With particular reference to Figs. 5 and 6 the intermediate web portion for each of the back fingers sections 25 and 26 also terminate short of the tips thereof and form marginal indentations 45 and 46 respectively which correspond in form to the indentations 17 and 21 respectively in the palm section.

It will therefore be noted that a deep and solid pocket 47 (Fig. 2) is formed in the glove between the thumb 13 and the index and middle finger portions 14 and 15 respectively which precludes the separation of said fingers and materially reduces the bending back of the user's said gloved fingers adjacent the pocket. The web 16 between the index and middle fingers is reenforced by a similar web 25 disposed at the finger backs which tend to strengthen and reenforce said web portion 16 formed in the palm section. As is most clearly illustrated in Figs. 1, 2 and 3, the web 16 and the intermediate web portion of the back fingers section 25 terminate short of their finger tips to provide a marginal indentation between said fingers, said indentation simulating the conventional space between the fingers of fielder's gloves and the like, and also functioning to provide the glove with relatively flexible finger tips for the particular purpose of catching a ball moving along the ground.

What is claimed is:

1. In a baseball glove for protecting a player's hand, the combination of an outer casing having an integral palm section and a composite back, said palm section having finger portions and side extensions, each of the latter covering substantially the outer rear half of the index finger and the little finger, a deep slit formed in the palm section between the middle and ring finger portions and extending inwardly to the crotch between the corresponding fingers of a player's hand, a web interconnecting the index finger portion and the middle finger portion of the palm section, a second web interconnecting the ring finger portion and the little finger portion of the

palm section, said webs forming a solid section between the respective finger portions from the palm outwardly to substantially the finger tips to provide shallow indentations in the palm section 5 between said interconnected finger portions, the composite back having a finger back section disposed adjacent each side thereof, means for securing the longitudinal outer-edge of each back section to the adjacent edge of the side extension, one of said finger back sections extending transversely to the center of the middle finger, and said other finger back section extending transversely to the center of ring finger, and each having a solid web coinciding with an interconnecting web of the palm section, intermediate finger back sections connecting the inner edges of the finger back sections and having a deep slit therein corresponding to and disposed behind the slit in the palm section, and a sewed seam 15 securing the marginal edge of the palm finger portions to the adjacent edge of the composite fingers back section.

2. A baseball glove of the kind described in claim 1 in which the composite back has a hand hole formed therein, and the finger back sections and the intermediate finger back sections, all extend rearwardly to the margin of the hand hole.

3. In a baseball glove construction for protecting a player's hand the combination of an outer casing having an integral palm section, a pair of spaced dual finger members extending from the palm section, a deep slit formed in the palm section between the members and extending inwardly to the crotch between the player's fingers, said dual finger members each having a centrally disposed, shallow indentation in the outer marginal edge thereof, side extensions for the palm section covering the rear outer half of the end fingers, spaced finger back sections each joined along an adjacent edge to a side extension, and being of a width to extend transversely to the center of the next inner finger, said finger back sections each having an indentation in the outer marginal edge disposed in registry with an indentation 30 a central back section for covering the inner half of the inner fingers, and having a deep slit therein coinciding with the slit between the dual finger members, means for joining the longitudinal marginal edges of the central section to the adjacent edges of the finger back sections, and means for securing the marginal edge of the dual finger members to the outer marginal edges of the finger back sections and the central section.
